UNITED STATES PATENT OFFICE.

FRANKLIN F. BRADLEY, OF CHICAGO, ILLINOIS, ASSIGNOR TO BRADLEY & VROOMAN COMPANY, OF CHICAGO, ILLINOIS, A CORPORATION OF ILLINOIS.

APPARATUS FOR COATING OBJECTS WITH SUBDIVIDED MATERIAL.

1,104,471.

Specification of Letters Patent.

Patented July 21, 1914.

Application filed October 14, 1911. Serial No. 654,679.

To all whom it may concern:

Be it known that I, FRANKLIN F. BRADLEY, citizen of the United States, residing at Chicago, in the county of Cook and State 5 of Illinois, have invented a certain new and useful Improvement in Apparatus for Coating Objects with Subdivided Material, of which the following is a full, clear, concise, and exact description, reference being had 10 to the accompanying drawings, forming a part of this specification.

My invention relates to apparatus for coating objects with comminuted, subdivided or powdered material and is of particular 15 service in spreading bronze powder upon objects whose surfaces are coated or covered or painted with suitable adhesive material or paint, which in its fresh state holds the powder scattered thereupon and 20 in its dry state firmly fixes the powder in place.

I have filed other applications relating to the coating of objects with subdivided material that are now pending and which 25 are listed as follows: Serial No. 543,215, filed February 11, 1910, Serial No. 550,115, filed March 18, 1910, Serial No. 603,726, filed January 21, 1911, Serial No. 611,042, filed February 27, 1911, and Serial No. 30 588,731, filed October 24, 1910.

I will explain my invention more fully by reference to the accompanying drawings showing the preferred form of apparatus which is employed.

35 In the drawings Figure 1 is a sectional elevation of the preferred form of apparatus; Fig. 2 is a sectional view on line 2-2 of Fig. 1; and Fig. 3 is an elevation, illustrated on a smaller scale than Figs. 1 and 40 2, of the apparatus.

Like parts are indicated by similar characters of reference throughout the different figures.

A receptacle *a* preferably has its interior 45 surface curved substantially throughout, this curvature being preferably spherical. The receptacle is desirably made of sheet metal and is therefore preferably globular in form. The receptacle substantially confines a body 50 of air within its interior, a door *a*¹ being preferably employed for substantially completely closing the receptacle, this door being of such a size as to permit the objects that are to be coated with the subdivided 55 material to be passed through the door open-

ing as these objects are placed within and withdrawn from the receptacle. It is understood that the receptacle is preferably stationary and that it may contain suitable supports for the objects that are to be 60 coated. The machine illustrated is adapted particularly to the application of subdivided material, such as bronze powder, to the sized surfaces of metal beds, a support *a*² suitable for the location of bed structures thereupon being employed. I employ fans *b* at the horizontal poles of the globular structure, these fans being known as Cone fans which are obtained upon the market from the Buffalo Forge Company, of Buffalo, 70 New York. These fans are mounted upon shafts *b*¹ that are driven by the belts *b*² in the directions indicated by the arrows illustrated upon the belts.

The object having a multiplicity of surfaces to be coated such as those with which a metal bed end *c*, for example, is provided, is supported within the receptacle upon the object support *a*², the object *c* having first received a coating of suitable adhesive material such as wet varnish. The object is thus substantially surrounded in substantially all planes by the body of gas. The subdivided material, such as bronze powder, is admitted to the receptacle interior 85 through the channels *d*. The object *c*, which is located between the fans *b*, has air directed thereupon by the fans in streams of opposite directions, the opposing streams of air mingling at the bed end *c* and there 90 thoroughly distributing bronze powder which is carried by the air, upon the bed end. The bronze powder is carried by the air and the air which carries the bronze powder is moved by the fans in the manner 95 described so that the air will carry the particles of bronze powder that float therein to the coated object where the particles of bronze powder will settle. I speak of the bronze powder as floating upon the air, 100 meaning that the air has floating action upon the bronze powder for a sufficient length of time to enable the air to carry the bronze powder to the parts that are to be coated therewith. It is possible for the 105 particles of bronze powder to settle in the course of time but owing to the curvature of the interior of the casing the currents of air are so directed toward the fans that any particles which have settled will be 110

caught up and returned to the streams of air flowing toward the object that is to be coated. The curved surface readily guides the air toward the fans after the fans have 5 discharged the air toward the object to be coated so that friction is much reduced and the power which is required to operate the fans is greatly lessened.

I prefer at first to operate the fans at 10 equal speeds, say 700 revolutions per minute, so that opposing streams of air are directed toward the object to be coated at substantially equal pressures, the fans being of similar capacity and operating to force air at 15 equal pressures when running at equal speeds, these opposing streams of air mingling at the object *c* and there effecting thorough distribution of the bronze particles to enable these bronze particles to reach all 20 of the surfaces that are coated with adhesive material. To improve and make more certain the results of the operation I also operate the left hand fan at a speed of say 350 revolutions and the right hand fan at 1,200 25 revolutions and thereafter reverse these speeds so as to cause the left hand fan to rotate at 1,200 revolutions per minute and the right hand fan at 350 revolutions per minute. In this way the stream of air whose 30 passage is forced by each fan alternately predominates over and is alternately predominated over by the stream due to the other fan so that the particles of subdivided material are with certainty conveyed to all 35 parts of the object to be coated that are provided with adhesive material. After the object has been left within the receptacle a sufficient length of time to enable it to be coated, the belts *b*² are shifted to loose pulleys and the fans *b* are allowed sufficiently to 40 slow down or to stop whereafter the door *a*¹ is opened and the object which is then coated with subdivided material is withdrawn.

The blades of the fans are so shaped as to 45 enable the fans to force the air to move from them in comparatively definite directions toward and by the object to be coated, the interior surface of the receptacle coöperating with the fans to effect return of the air to 50 the same.

The fans are placed in such proximity as to enable each of them effectively to carry the material-laden gas beyond the object to be coated which is interposed between the

fans whereby effective mingling of the opposing streams of gas occurs at such object whereby the object may be thoroughly coated with the subdivided material carried by the gas. 55

Air or any other gas which is inert with 60 respect to the substances may be employed, and I use the term air in the claims in this broad sense.

While I prefer fans *b* of the precise construction shown for accomplishing the results which are the object of my invention, I do not wish to be limited to the employment of these instrumentalities within the receptacle for defining the general path followed by the air where it has fullest flow, 70 and while the blades of the fans are, by reason of their entire location within the receptacle, particularly well adapted to effect return movement of the air to the fans, I do not wish to be limited to the employment of 75 fans within the receptacle interior.

Claims relating to the processes herein disclosed are presented in my co-pending applications Serial No. 654,678, filed October 14, 1911 and Serial No. 665,955, filed December 15, 1911. 80

Having thus described my invention, I claim as new and desire to secure by Letters Patent the following:

1. Apparatus for coating objects with subdivided material carried by air including a receptacle for the objects whose interior surface is substantially curved throughout; and means for effecting the forced passage of air within the receptacle to enable the air to 90 convey subdivided material to the object that is to be coated therewith. 85

2. Apparatus for coating objects with subdivided material carried by air including a receptacle for the objects whose interior surface is substantially spherical throughout and means for effecting the forced passage of air within the receptacle to enable the air to convey subdivided material to the object that is to be coated therewith. 95

In witness whereof, I hereunto subscribe my name this tenth day of October, A. D., 1911. 100

FRANKLIN F. BRADLEY.
